OR. D 13,393

Design No. 13,393, dated November 7, 1882.

UNITED STATES PATENT OFFICE.

HENRY BOSSHARDT, OF NEW YORK, N. Y., ASSIGNOR TO THE KURSHEEDT MANUFACTURING COMPANY, OF SAME PLACE.

DESIGN FOR EMBROIDERY.

SPECIFICATION forming part of Design No. 13,393, dated November 7, 1882.

Application filed September 28, 1882. Term of patent 7 years.

To all whom it may concern:

Be it known that I, HENRY BOSSHARDT, of New York, in the county and State of New York, have invented a new and original Design for an Embroidery, of which the following is a specification.

The accompanying photograph represents a face view of my new embroidery.

This invention relates to a new embroidery representing a parrot; and it consists of the new arrangement and configuration of the parts of which the bird is composed, as hereinafter described.

The letter A in the accompanying photograph represents the head of the animal; B, the body, and C the tail. The head A is composed of representations of feathers, which, near the spot representing the eye, are of segmental form, as shown more fully at a, the embroidery-threads in each segment running substantially parallel with the radius thereof. These segmental parts a join the body B to the head by means of radiating threads b, which are distinctly visible on the photograph, and which produce, in connection with the rest of the design, a very peculiar effect. From the body B extend the tal-

ons d, which are also composed of embroidery-threads, the tail-feathers C, and the end feathers e of the wing. The feathers are all represented by embroidery-threads traversing them obliquely from edge to edge; but that feature is not here claimed, because it is claimed in another application filed by me at the same time with this, and marked application A.

I claim—

1. The design for an embroidery representing a bird, the same consisting of the representation of the head A, segmental representations of feathers a, and body B, substantially as shown.

2. The design for the representation of a bird, having the radiating threads b and the body B, substantially as shown.

3. The design for the representation of a bird, consisting of the head A, segmental feathers a, threads b, body B, talons d, wing e, and tail C, substantially as shown.

HENRY BOSSHARDT.
